UNITED STATES PATENT OFFICE.

ROBERT L. TATE, OF ATLANTA, GEORGIA, ASSIGNOR OF ONE-HALF TO JAMES M. HACKNEY, OF ATLANTA, GEORGIA.

LOCOMOTIVE-ECCENTRIC-LUBRICATING DEVICE.

1,165,215.

Specification of Letters Patent. Patented Dec. 21, 1915.

Application filed May 1, 1915. Serial No. 25,245.

To all whom it may concern:

Be it known that I, ROBERT L. TATE, a citizen of the United States, residing at Atlanta, in the county of Fulton and State of Georgia, have invented certain new and useful Improvements in Locomotive-Eccentric-Lubricating Devices; and I do hereby declare the following to be a full, clear, and exact description of the invention, such as will enable others skilled in the art to which it appertains to make and use the same.

This invention relates to devices for lubricating locomotive eccentrics, and the primary object of the invention is to provide a device wherein the lubricant is fed, by gravity, to a flanged receptacle positioned in close proximity to and supported by the frame of the locomotive eccentric, for feeding lubricant to the eccentric and preventing the same from flying away from the eccentric or being blown away by the force of the current of air generated by the travel of the locomotive.

Another object of this invention is to provide means whereby the quantity of lubricant fed to the eccentric may be limited or regulated as desired.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:

Figure 1 is a view showing the lubricating device applied to a locomotive, Fig. 2 is an enlarged fragmentary view of the lubricating device, Fig. 3 is a fragmentary view of the lubricating device, showing the means for preventing the wind blowing the lubricant from the eccentric, and Fig. 4 is a vertical section through the lubricant protector.

Referring more particularly to the drawings, 1 designates an ordinary locomotive engine, which has the usual type of boiler construction 2. The boiler 2 of the engine, has a pair of bars 3 and 4 mounted thereon, rearwardly of the stack 5, which bars have a plate or platform 6 secured to their upper surfaces, upon which rests a lubricant re-

taining receptacle 7. The lubricant retaining receptacle 7 has a removable screw cap 8 which forms a closure for the upper open end of the receptacle and permits of the filling of the receptacle with lubricant.

The lubricant retaining receptacle 7 has a pipe 9 communicating therewith adjacent to its upper end. The pipe 9 has its outer end flared, as is shown at 10, to form an enlarged mouth for permitting of the passage of air into the receptacle 9 for insuring the efficient outflow of lubricant therefrom. A screen 11 is mounted across the opening of the flared end 10 of the pipe 9, and is provided for preventing cinders, dust or the like from passing into the receptacle 7 through the pipe 9.

The receptacle 7 has an outlet pipe 12 communicating with the lower end thereof, in which pipe is interposed a regulating valve structure 13. The regulating valve structure 13 is of the ordinary type employed for regulating the quantity of lubricant passing therethrough. The pipe 12 has communication with a sight feed cylinder 14, which is constructed of glass, or other transparent material, through which the lubricant passes, until it leaves the regulating valve structure 13. A pipe 15 is connected to the lower end of the sight cylinder 14, and extends downwardly through the boiler shelf, as is shown at 16, in Fig. 1 of the drawings. The pipe 15 has its lower end detachably connected to a substantially frusto-conically shaped shell 17, as is shown at 18. The shell 17 has its apex positioned downwardly, and a nipple 19 is connected thereto, which extends into and through the supporting frame 20 of the eccentric 21 of a locomotive, for permitting of the passage of the lubricant through the shell 17 and through the eccentric for properly lubricating the same. The shell 17 is provided for preventing a current of air generated by the travel of the locomotive, from blowing the drops of lubricant out of the path to the eccentric 21.

Any desired number of outlet pipes 12, may be employed, as the requirements will necessitate, depending upon the number of eccentrics to be lubricated.

The sight cylinder 14 is protected by metallic rods 23, which are positioned about the outer surface of the cylinder or sleeve at spaced intervals, as is clearly shown in Fig.

2 of the drawings, and connected to plates 24 and 25, which are mounted upon the upper and lower ends of the cylinder.

From the foregoing description taken in connection with the accompanying drawings the advantages of construction and of the method of operation of the improved locomotive eccentric lubricating device will be readily apparent to those skilled in the art to which this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

What is claimed is:—

1. In a device for lubricating locomotive eccentrics, a lubricant retaining receptacle, a pipe communicating with the upper portion of said receptacle, said pipe having its outer end flared, a foraminous screen mounted across the mouth of said flared end, said pipe provided for conducting air into said receptacle for facilitating the outflow of lubricant therefrom.

2. In a device for lubricating locomotive eccentrics, a lubricant retaining receptacle,

a pipe communicating with the upper portion of said receptacle, said pipe having its outer end flared, a foraminous screen mounted across the mouth of said flared end, said pipe provided for conducting air into said receptacle for insuring the outflow of lubricant therefrom, a pipe communicating with the lower end of said receptacle, a regulating valve structure interposed in said pipe, a sight cylinder interposed in said pipe, said last named pipe provided for communication with a locomotive eccentric.

3. In a device for lubricating locomotive eccentrics, a lubricant retaining receptacle, a pipe communicating with said receptacle, a regulating valve structure interposed in said pipe, a substantially frusto-conically shaped shell secured to the outlet end of said pipe, a nipple secured to the apex of said frusto-conical shell for communicating with a locomotive eccentric, a sight cylinder interposed in said pipe, and a pipe communicating with the upper end of said receptacle, said pipe having its outer end flared, and a meshwork screen secured to the open flared end of said pipe.

In testimony whereof I affix my signature in presence of two witnesses.

ROBERT L. TATE.
